UNITED STATES PATENT OFFICE.

ABRAM D. BEATY AND WILLIAM H. CALKINS, OF PAINTED POST, N. Y.

BUCKWHEAT-HULLING APPARATUS.

SPECIFICATION forming part of Letters Patent No. 234,113, dated November 9, 1880.
Application filed February 19, 1880.

To all whom it may concern:

Be it known that we, ABRAM D. BEATY and WILLIAM H. CALKINS, of Painted Post, in the county of Steuben and State of New York, have invented certain new and useful Improvements in Buckwheat-Hullers; and we do hereby declare that the following is a full, clear, and exact description of the invention, which will enable others skilled in the art to which it appertains to make and use the same, reference being had to the accompanying drawings, and to the letters of reference marked thereon, which form a part of this specification.

15 This invention relates to an improvement in buckwheat-hullers, having for its object to remove in the most expeditious and effective manner the hulls from buckwheat; and it consists in the construction and arrangement 20 of parts, as will be hereinafter more fully set forth.

In the annexed drawings, Figure 1 is a central vertical section. Fig. 2 is an end elevation; and Fig. 3 is a detail view.

25 In the drawings; A indicates the upright standards; B, the side pieces, and C the cross-pieces, of the frame; D, revolving serrated cylinder; E, hopper; F, hinged serrated sections; G, standards supporting the rod on which the 30 sections are hinged; H', metal plate to which standards are attached; H, thumb-screw; I, rubber cushion provided with metal head; K, ears on plate H', through which the thumb-screws pass; L, bearings for the journal of 35 the serrated cylinder; M, shaking-screen; N, springs supporting shaking-screen; O, spout attached to bottom of shaking-screen; a, lip on forward part of plate H', to limit the forward movement of the sections; b, slotted 40 bearing for the ends of plate H', and c adjusting-screws for the same.

The frame may be of any ordinary or desired construction, across the upper portion of which is the serrated cylinder D, secured 45 in suitable bearings on the side pieces of the frame.

To a plate, H', extending across the frame on a line with the serrated cylinder, are secured a desired number of sections, F. These 50 sections are serrated at their lower ends and

made concave to conform to the shape of the cylinder, as shown. They are supported upon the plate H' by means of standards G, secured thereto, which support a rod upon which the sections are hinged.

The sections are adjusted to suit different sizes of grain by means of thumb-screws H, which work against the rubber cushions I, which rest against the sections. These cushions are provided with metal heads to prevent the wearing of the material.

The plate H' is capable of adjustment by means of the screws c, arranged as shown. A lip, a, upon the plate H', limits the forward motion of the hinged sections.

The machine may be run by hand or power, as desired. By this arrangement a graduated closing of the spaces between the convex surface of the revolving cylinder and the concave surfaces of the hinged sections, both being 70 serrated, imparts to the grain the requisite rolling motion for the desired distance before they reach the narrowest portion between the two surfaces, thereby securing a perfect abrasion of the buckwheat without danger of 75 breaking or pulverizing the shells and making it difficult to separate from the broken meats.

The hinged sections being independent of each other, with each one provided with self-adjusters, prevents waste and enables a wider space between the crushing-surfaces.

Having thus fully described our invention, what we claim as new, and desire to secure by Letters Patent, is—

In a machine for hulling buckwheat, the serrated or fluted revolving cylinder D, working in adjustable bearings L, in combination with the hinged serrated sections F, standards G, plate H', having ears K, thumb-screws H, and metal-headed rubber cushions I, all as and for the purpose set forth.

In testimony that we claim the foregoing as our own we have hereto affixed our signatures in presence of two witnesses.

ABRAM D. BEATY.

WILLIAM H. CALKINS.
